[57] CLAIM

The ornamental design for an exerciser seat, as shown and described.

DESCRIPTION

FIG. 1 is a top, front isometric view of an exerciser seat showing my new design;

FIG. 2 is a front view thereof;

FIG. 3 is a left side view thereof;

FIG. 4 is a rear view thereof;

FIG. 5 is a top plan view thereof; and,

FIG. 6 is a bottom view thereof.

The side elevational view from the right side of the seat is a mirror image of the side view shown in FIG. 3.

FIG. 1

FIG. 2

FIG. 3

FIG. 4

FIG. 5
